HOWARD M. BARBER, OF PAWCATUCK, CONNECTICUT, ASSIGNEE TO C. B. COTTRELL & SONS COMPANY, OF WESTERLY, RHODE ISLAND, A CORPORATION OF DELAWARE.

SHEET-FOLDING MECHANISM.

Application filed April 2, 1927. Serial No. 180,500.

In sheet folding mechanism where coacting floating folding jaws and blades are used to impart the fold to the sheet or group of sheets, it is well known that as the folding jaws approach their folding point the centrifugal force of the jaws tends to move the roller of their floating control lever away from the inner wall of its cam groove and against the outer wall thereof, thereby causing an uneven and noisy action of the parts and also undue wear thereon. These undesirable features are caused by the fact as the faces of the folding jaws are brought to their radial position at their folding point, their center of gravity will be back of the center of their supporting bearings and as the faces of the jaws are brought to their tangential position at their releasing or delivery point, their center of gravity will be ahead of the center of their supporting bearings.

The object of my invention is to provide means for ensuring the even and quiet action of the parts with a minimum wear thereof. My invention, therefore, comprises intermittently acting counterbalancing means for counteracting the centrifugal force of the folding jaws during a predetermined arc of the radial path of said jaws for ensuring the even and quiet action of the parts hereinabove referred to.

My invention more particularly comprises spring pressed yielding means arranged to act on the folding jaws to counteract their centrifugal force during that portion of their rotary travel in which they are oscillated to float them to and from their radial or folding position; by preventing the roller of the jaw floating control lever from being thrown outwardly away from the inner wall and against the outer wall of its cam groove during this portion of the rotary movement of the jaws.

A practical embodiment of my invention is represented in the accompanying drawings, in which

Fig. 1 represents a cross section through the folding jaw carrier adjacent one end thereof, one pair of floating folding jaws being in the position they assume at the folding point.

Fig. 2 represents a detail similar view on an enlarged scale,

Fig. 3 represents a detail section taken in the plane of the line III—III of Fig. 2 looking in the direction of the arrows.

Fig. 4 represents in elevation the lever for controlling the opening and closing of the folding jaws.

Fig. 5 represents a cross section taken in the plane of the line V—V of Fig. 4 looking in the direction of the arrows.

The floating folding jaws of each pair are denoted by 1, 2, which jaws are mounted to oscillate in the usual manner in suitable bearing supports 3, fixed to the rotary carrier 4, which carrier in the present instance is shown as of the yoke type and as carrying four pairs of folding jaws.

The jaw floating control lever 5 is provided with the usual roller 6 arranged to travel in the endless groove 7 of the stationary box cam 8 for oscillating the jaws to float them into and out of their folding position. This box cam groove 7 is so shaped and the floating folding jaws are so mounted that unless the centrifugal force of the jaws is counteracted, the roller 6 will be forced away from the inner wall and against the outer wall of the cam groove 7 as the jaws are brought to their folding position, thereby causing an uneven and noisy action of the parts as well as considerable wear thereon.

The intermittently acting counterbalancing means which I have shown for counteracting this centrifugal force is as follows:

A bell crank lever is pivoted at 9 on the rotary carrier 4 adjacent to its pair of folding jaws 1, 2. A pressure spring 10 exerts its tension against one arm 11 of the bell crank lever, the other arm 12 of said lever having its outer end positioned to engage an abutment 13 on the folding jaw 1 as the jaws are being floated into and out of their folding position. The tension of this spring 10 may be regulated to exert the required pressure on the abutment 13 of the folding jaw 1 to hold the roller 6 against the inner wall of its cam groove 7 as the folding jaws are moved into and out of their folding position.

The opening and closing of the folding jaws as they are moved to and from their folding position is controlled by the lever 14 projecting from the rock shaft 15 to which the folding jaw 2 is secured, said

lever being provided with a roller 16 arranged in position to be engaged by the stationary cam 17. A spring 18 exerts its tension on the lever 14 for yieldingly holding the folding jaws closed.

The dotted line 19 represents the folding cylinder and the dotted lines 20, 21 and 22 represent the cylinders which coact therewith.

- 10 It is evident that various changes may be resorted to in the construction, form and arrangement of the several parts without departing from the spirit and scope of my invention; hence, I do not wish to be limited 15 to the particular embodiment herein shown and described, but

What I claim is:—

1. In a sheet folding mechanism, floating folding jaws, and means for counteracting 20 their centrifugal force during a predetermined arc of their rotary path.

2. In a sheet folding mechanism, floating folding jaws, and yielding means for counteracting their centrifugal force during 25 a predetermined arc of their rotary path.

3. In a sheet folding mechanism, floating folding jaws, and counterbalancing means arranged to engage one of the jaws during a predetermined arc of their rotary path to 30 counteract their centrifugal force.

4. In a sheet folding mechanism, floating folding jaws, and yielding counterbalancing means arranged to engage one of the jaws during a predetermined arc of their rotary 35 path to counteract their centrifugal force.

5. In a sheet folding mechanism, a rotary carrier, floating folding jaws mounted thereon, and a spring pressed bell crank lever mounted on the carrier and arranged to engage one of the jaws during a predetermined 40

arc of their rotary path to counteract their centrifugal force.

6. In a sheet folding mechanism, a stationary box cam, a rotary carrier, floating folding jaws mounted thereon, a jaw floating lever having a roller arranged to travel in the box cam groove, and means on the rotary carrier arranged to engage one of the jaws during its floating movement for counteracting the centrifugal action of the 50 jaws and holding said roller against the inner wall of its cam groove to ensure an even and quiet action of the parts.

7. In a sheet folding mechanism, a stationary box cam, a rotary carrier, floating folding jaws mounted thereon, a jaw floating lever having a roller arranged to travel in the box cam groove, and yielding means on the rotary carrier arranged to engage one of the jaws during its floating movement for 55 counteracting the centrifugal action of the jaws and holding said roller against the inner wall of its cam groove to ensure an even and quiet action of the parts.

8. In a sheet folding mechanism, a stationary box cam, a rotary carrier, floating folding jaws mounted thereon, a jaw floating lever having a roller arranged to travel in the box cam groove, and a spring pressed bell crank lever on the rotary carrier arranged to engage one of the jaws during its floating movement for counteracting the centrifugal action of the jaws and holding said 60 roller against the inner wall of its cam groove to ensure an even and quiet action of 70 the parts.

In testimony, that I claim the foregoing as my invention, I have signed my name this 30th day of March, 1927.

HOWARD M. BARBER.
